DESIGN FOR A COMBINED TOP, BACK GUARD PANEL, TIMER, AND UTILITY COMPARTMENT FOR A COOKING RANGE

Laird F. Covey, Stamford, Conn., assignor to Boston Stove Foundry Company, Reading, Mass., a corporation of Massachusetts

Application February 6, 1948, Serial No. 144,335

Term of patent 14 years

(Cl. D81—25)

To all whom it may concern:

Be it known that I, Laird F. Covey, a citizen of the United States, residing at Stamford, in the county of Fairfield and State of Connecticut, have invented a new, original, and ornamental Design for a Combined Top, Back Guard Panel, Timer and Utility Compartment for a Cooking Range, of which the following is a specification, reference being had to the accompanying drawing, forming part thereof.

In the drawings:

Fig. 1 is a perspective view of the combined top, back guard panel, timer and utility compartment for a cooking range showing my new design;

Fig. 2 is a perspective view of the back guard with its condiment shelf cover shown in open position, the top of the stove proper being indicated in dotted lines; and

Fig. 3 is an end elevation of the combined top

back guard panel, timer and utility compartment for a cooking range as shown in Fig. 1.

The dominant features of the design reside in the portions shown in full lines.

I claim:

The ornamental design for a combined top, back guard panel, timer, and utility compartment for a cooking range, as shown and described.

LAIRD F. COVEY.
